LOOSE LEAF-RETAINING CLIP FOR
BILLFOLD ASSEMBLIESRene Maurice Schupbach, Providence, R. I., and
Sol H. Kohen, Los Angeles, Calif.; said Schup-
bach assignor to said Kohen

Application April 4, 1944, Serial No. 529,467

1 Claim. (Cl. 150—38)

1

This invention relates to a billfold and more particularly to means for attaching card or window sections to the billfold.

Heretofore in the use of a billfold which is equipped with one or more window sections, the one, two, or more window sections are attached to the billfold by some lacing means necessitating eyeleting of the parts to be attached and some lacer to connect them together. The usual lacer may be a shoe string or something similar. This assembly is a clumsy attachment of the parts and requires considerable time for attaching or detaching the window sections with reference to the billfold.

One of the objects of this invention is to provide assemblies which may be quickly and easily had.

Another object of this invention is to provide mechanical assemblies, making unnecessary the use of eyelets or a lacer.

Another object of this invention is to provide an arrangement so that one, two, three, or more sections may be assembled with the billfold or easily and quickly detached therefrom selectively as desired.

Another object of the invention is to provide a device by which the parts are assembled which will be neat and inconspicuous yet effective in the performance of its functions.

With these and other objects in view, the invention consists of certain novel features of construction, as will be more fully described and particularly pointed out in the appended claim.

In the accompanying drawings:

Fig. 1 is a top plan view of the billfold in folded position;

Fig. 2 is a perspective view of the billfold in open position and showing the same as suspended from the chain which is shown in Fig. 1;

Fig. 3 is a perspective view of the attaching clip or members used for assembling the sections;

Fig. 4 is a plan view of one of the detachable sections;

Fig. 5 is a section on line 5—5 of Fig. 4;

Fig. 6 is a section on line 6—6 of Fig. 4;

Fig. 7 is a sectional view on line 7—7 of Fig. 2;

Fig. 8 is a fragmental view of the clip on the billfold with the sections removed.

In proceeding with this invention we have provided a clip which may be easily slipped over one of the walls of a billfold and into which additional separable sections may be easily assembled along their fold line so that their fold line will

2

be held to the hinge or fold line of the billfold in a book-like assembly of the parts.

With reference to the drawing, the billfold proper is designated generally 10 and consists of an outer wall 11 and an inner wall 12 which walls are sewed together along their ends 13 and along the bottom 14 while partition 15 and additional card-retaining means 16 may be assembled with the walls by the sewing which is provided for attaching them. Additional sewings as at 18 may be provided for the attachment of the card-receiving pocket. The walls 10 and 11 are foldable as at 19 and 20 to provide a hinge portion so that the billfold may be doubled upon itself in a generally book-like formation.

The inner wall 12 is detached from the outer wall 11 along the hinge portion at its upper edge 21 and also at its lower edge 22 so that these edges are free from the outer wall 11 and it is about this portion that the clip-like member for securing additional sections in position is located. This clip-like member is designated generally 25 and shown in Fig. 3 in perspective. It comprises a member 26 having a hook 27 at one end while it is folded as at 28 along an arc to provide resilience and proceeds to form a member 29 extending a part of the length of the member 26, with its end flared outwardly as at 30 to provide a mouth 31 for the reception of the added parts thereinto.

This member 25 is positioned about the hinge portion of the wall 12 by locating the member 26 between the walls 11 and 12 and the member 29 on the inner portion of the wall 12, while the hook 27 extends over the edge 22 of the wall 12 so that the wall is embraced by the member. The wall 12 is of a width or dimension so that it will engage the inner edge of the hook 27 and the arc 28 to prevent the member from sliding from the wall. The lip 30 extends outwardly from the wall, as shown in Fig. 7, so that sheet-like portions may be slid beneath the member 29.

The window-like sections which we assemble with the bill fold are designated generally 32, as shown in plan view in Fig. 5. Each of these consists of a part 33 and a part 34 which are joined together by hinge portion 35 so that these parts may be folded one on the other in a manner similar to that of folding the bill fold along its hinge portion. This hinge portion 35 of the sections, or for a plurality of sections if desired, may be assembled with the bill fold by sliding this hinge portion 35 beneath the lip 30 and along under the member 29 until it has reached the folded portion 28 and then the opposite edge may

be tucked beneath the hook 27 whereby a complete assembly of the parts is provided. Several sections may be provided if it is desired to secure additional sections in the bill fold. We have illustrated in Fig. 2 two such sections but it will be understood that additional sections may be provided to the extent that the book-like parts may be necessary for carrying cards or the like desired.

Each of the sections 33 and 34 comprise trans-parent parts 36 and 37 open as at 38 at one edge while secured by bindings 39 along their sides so that cards may be slipped into the open mouth 38 to be viewed through the windows 36 by merely opening the bill fold in a book-like manner.

If desired, a flexible member such as a chain 40 may be attached by a ring 41 to the arched bend-able portion 28 while a clip 42 may be provided for attachment to the belt at its opposite end.

We claim:

A bill fold having opposite walls secured to each other in a manner to provide a pocket in which bills are received, a spring clip having a pair of arms connected and located on opposite sides of one of said walls, one of said arms having a hook to extend over one edge of the wall and

the other of said arms extending substantially to but short of said hook having a free end turned outwardly facing the hook and providing a mouth for the reception and removal from between it and its embraced wall of a separable foldable element with the fold being in alignment with said arms.
